UNITED STATES PATENT OFFICE.

HEINRICH SPINDLER, OF BOBLINGEN, NEAR STUTTGART, GERMANY.

PROCESS FOR WASHING AND CLEANING FABRICS AND THE LIKE.

No Drawing. Application filed June 1, 1923, Serial No. 642,875, and in Germany June 1, 1922.

This invention relates to a process for washing and cleaning fabrics and other material with hard water.

It is generally known that when washing fabrics with hard water, which is water having a more or less high content of calcium- and magnesium salts, these salts react with the soap, which consists usually of mixtures of soluble alkali salts of fatty acids, and produce insoluble calcium- and magnesium salts of the fatty acids. This involves various disadvantages. A rather considerable percentage of the valuable alkali salts of fatty acids is rendered inoperative by the transformation of the fatty acids into the insoluble salts so that they are prevented from fulfilling their purpose which is to produce a cleaning effect. Furthermore the insoluble calcium- and magnesium salts deposit upon the fibres, fabrics and the like, as a tough, viscous mass, enveloping the dirty substances so that they cannot be acted upon by the soap, and rendering the fibres brittle after the drying, dull in colour and less easily dyed. According to the degree of hardness of the water the normal progress of the washing process is therefore disturbed more or less and the qualities of the fabrics are more or less unfavorably influenced in chemical and physical respect. For this reason the washing water has been hitherto always submitted to a softening process before it is used for washing.

It has been found that the washing process will take place in a normal manner and without any of the above mentioned disadvantages with hard or even very hard water, if soaps are used for washing which contain insoluble metal compounds of a feebly basic character such as for instance oxides or hydroxides of magnesium, calcium, barium, aluminium, zinc and the like. These insoluble substances can be incorporated in soaps in the simplest manner for instance by adding to the elementary substances of the soaps, before or during the saponification, salts or double salts of the metals in question, which are soluble in water, for instance magnesium sulphate, such quantities of said salts being added as are necessary to react with the alkali to form the desired amount of metal oxide or hydroxide, so that the water is softened during the washing process.

As an example a determined quantity of fatty acids is heated with such a quantity

of alkaline lye that the alkali present in the lye is sufficient for the saponification of the fatty acid and for the transformation of the soluble salt added.

The action of the water-insoluble metal compounds may be explained according to the following theory, it being understood that the invention is not dependent upon this or any other theory: The hardness-constituents commonly present in hard water are the acid carbonates (i. e., "bicarbonates") of calcium and/or magnesium. The finely divided water-insoluble metal compounds added to the hard water in the soap vehicle react with the said acid carbonates, thereby forming water-insoluble normal carbonates, as illustrated by the following equation:

The quantities of insoluble metallic combinations to be incorporated in the soap depend evidently on the hardness of the water.

It has been found by exhaustive experiments that relations exist between the quantity of metal salts incorporated in the soap and the degree of hardness of the water inasmuch as if, for instance, magnesium sulphate is added, each part of magnesium sulphate or $\frac{1}{6}$ part of magnesium oxide derived therefrom (if the usual and herein-after stated quantitative proportions are adhered to), precipitates a quantity of hardness-causing calcium and magnesium compounds which corresponds to the degree of hardness of the water.

In washing processes generally a soap solution is used which contains 100 gr. of soap to 10 liters (=10000 c. c.) of water. As the soap contains on an average of 50% of fatty acid, and as 1 degree of hardness corresponds to 1 gr. of calcium oxide (equivalent to 0.8 gr. of magnesium oxide) in 100,000 c. c. of water, the said 10 liters of soap solution contain 50 gr. of fatty acid, and to each degree of hardness, 0.1 gr. of calcium oxide or 0.08 gr. of magnesium oxide. If therefore 0.17 gr. of magnesium oxide are produced by adding 1 gr. of crystallized magnesium sulphate to every 100 gr. of fatty acid in the soap, the soap solution taken as an example contains 0.08 gr. of magnesium oxide incorporated in 50 gr. of fatty acid and capable of expelling from 10 liters of water 0.1 gr. of hardness—producing calcium oxide corresponding to 1 degree of hardness; that is, every gram of

crystallized magnesium sulphate which is incorporated in the soap to every 100 gr. of fatty acid, is capable—after having been converted to magnesium oxide—of removing 1 degree of hardness from the water when the soap is dissolved in the usual quantities (proportion 1:100).

Based upon this knowledge the soap can be adapted to any degree of hardness of the water so that for a water of, for instance, 40 degrees of hardness a soap is used which has an addition of 40 parts of magnesium sulphate, or about 6 parts of magnesium oxide, for 100 parts of fatty acid, or, to make quite sure, a soap which contains an excess, for instance up to 45 or 50 parts of magnesium sulphate, or about 6 parts of magnesium oxide, for 100 parts of fatty acid.

If the soaps containing insoluble metal oxides or the like are used for washing purpose, the calcium- and magnesium combinations dissolved in the water are separated in the form of a loose powder without the use of valuable fatty acids and without precipitation of insoluble fatty acid combinations upon the material to be washed, so that the quality of this material is not influenced unfavorably.

I claim:

30. 1. A process of washing and cleaning fab-

rics and other materials, which comprises washing the material in hard water with a soap containing a quantity of an uncombined finely divided water-insoluble metal compound of a weak basic character capable of precipitating calcium and magnesium compounds from the water, so that the water is softened during the washing process.

2. A process of washing and cleaning fabrics and other materials which comprises 40 washing the material in hard water containing an acid carbonate of an alkaline earth metal with a soap containing an uncombined finely divided water-insoluble metal compound having a weak basic character capable of reacting with the said acid carbonate, thereby precipitating the water-insoluble normal carbonate of said alkaline metal.

3. A process of washing and cleaning fabrics and other materials, as defined in claim 50 2, in which the said water-insoluble metal compound is magnesium oxide.

4. A process of washing and cleaning fabrics and other materials, as defined in claim 2, in which the said water-insoluble metal 55 compound is magnesium oxide.

In testimony whereof I have affixed my signature.

HEINRICH SPINDLER.
